United States Patent Office

Des. 204,718
Patented May 10, 1966

204,718

DISPLAY STAND

Steven T. Marchetti, 6802 Lincolnwood Drive,
Lincolnwood, Ill.

Filed Apr. 2, 1965, Ser. No. 84,580

Term of patent 7 years

(Cl. D80—10)

FIG. 1 is a perspective view of a display stand embodying my new design;

FIG. 2 is an elevational view thereof; and
FIG. 3 is a top plan view thereof.

I claim:

The ornamental design for a display stand, substantially as shown.
